(57) CLAIM

The ornamental design for a massage wand, as shown and described.

DESCRIPTION

FIG. 1 is a perspective view of a massage wand, showing my new design with a strap attached and it being shown in broken lines for illustrative purposes only and forming no part of the claimed design;

FIG. 2 is a side elevational view thereof with the strap removed;

FIG. 3 is a right end elevational view thereof;

FIG. 4 is a left end elevational view thereof;

FIG. 5 is a top view thereof; and,

FIG. 6 is a bottom view thereof.
